UNITED STATES PATENT OFFICE.

MICHAEL MARINO, OF NEW YORK, N. Y.

LOCK.

1,386,641.

Specification of Letters Patent. Patented Aug. 9, 1921.

Application filed September 8, 1919. Serial No. 322,278.

To all whom it may concern:

Be it known that I, MICHAEL MARINO, a citizen of the United States, residing at New York city, in the county of New York and State of New York, have invented certain new and useful Improvements in Locks, of which the following is a specification.

This invention relates to locks of the type known as mortise locks and has for its 10 principal object to provide a lock which is equally well adapted for both swinging and sliding doors.

Another object is to provide a lock having a bolt which interlocks with the keeper so 15 that an unauthorized person cannot, without the use of a proper key, operate the bolt and gain access to the premises.

With these and other objects in view, the invention consists in the novel details of 20 construction and arrangement of parts which will be more clearly understood from the following description and drawings in which,

Figure 1 is a vertical sectional view of my 25 invention showing the bolt disengaged.

Fig. 2 is a similar view showing the bolt in its locking position.

Fig. 3 is a top plan view of the latch mechanism.

Fig. 4 is a top plan view of the bolt.

Fig. 5 is a side elevational view of a tumbler.

Fig. 6 is a side elevational view of the bolt operating bar.

Fig. 7 is a side elevational view of another tumbler.

Fig. 8 is a sectional view of the bolt operating knob.

Fig. 9 is a plan view of the same.

Fig. 10 is a vertical sectional view of a modified form of my invention.

Fig. 11 is a similar view showing the bolt disengaged.

Fig. 12 is a side elevational view of the 45 main bolt as illustrated in Figs. 10 and 11.

Fig. 13 is a side elevational view of a secondary bolt illustrated in Figs. 10 and 11.

Fig. 14 is a side elevational view of the keeper, and

Fig. 15 is a side elevational view of the tumbler employed in Figs. 10 and 11.

My invention comprises a casing 1 which is provided with suitable guides 2 between which a sliding bar 3 moves backward and forward. This bar is provided with recesses

4 in which a lug 5 on a tumbler 6 falls to

arrest the bar in either its forward or rear position. This lug just described is clearly shown in Fig. 5.

The opposite edge of the sliding bar 3 is 60 provided with a notch 7 for the reception of a key from the outside by which the sliding bar is operated. In the same edge and in advance of the notch just described I provide a second notch 8 forming an abutment 65 for the extension 9 provided on the head 12 of a knob employed on the inside of the lock for operating the same from within. This knob, indicated at 10 on the drawing is clearly illustrated in Figs. 8 and 9 and 70 consists of a hollow spindle having a screw 11 passing through the same for detachably securing the head 12 in position.

Connected to the forward end of the sliding bar 3 is a link 13 forming a connection 75 with a bifurcated extension 14 of a pivoted lock bolt 15. This lock bolt is provided at its end with a hooked portion 16 which, when the bolt is swung downward in its locking position, engages the rear face of 80 the keeper plate 17 enabling the lock to be employed on either a sliding or swinging door. The link 13 previously described is pivotally connected to both the sliding bar and lock bolt so as to accomplish the swing- 85 ing movement just described.

Located in the upper part of the casing 1 is a latch bolt 18 slidably mounted in guides 25 and provided with a reinforcing web 19 having a spring receiving recess 20 for the 90 reception of a spring 20' which normally holds the latch bolt in its extended position for engagement with the aperture provided in the keeper plate 17. A spindle 21 is provided on which the door knobs, not shown, 95 are mounted. This spindle is provided with a head 22 and an arm 23 extending therefrom. A link 24 is pivotally connected to the arm 23 and the rear portion of the latch bolt 18 so that upon operation of the spindle the bolt 100 will be withdrawn from the aperture in the keeper plate. It will be noted that the link does not at any time assume a dead center, but is always at an angle to the longitudinal axis of the latch bolt so as to allow the 105 bolt to have free movement back and forth.

In Fig. 7 I have shown a fragment of a tumbler 26 which may be used instead of the tumbler 6 necessitating the use of a different key. The configuration of the tumblers 110 may be varied where it is desired to use different locks.

In Figs. 10 and 11 I have shown a casing 27 provided with guides 28 between which the sliding bolts 29 and 30 operate. The upper edges of the sliding bolts 29 and 30 are provided with recesses 31 for the reception of a lug 32 formed on the tumbler 33, which lug acts to hold the sliding bolt either in their locking or unlocking position. The opposite edge of each of the tumblers 10 is provided with recesses 34 for the reception of a key by which the bolts are shifted. Slightly in advance of the recesses 34 are similar recesses 35 for the reception of the extension 9 formed on the head 12 which is carried by the operating knob 10 clearly shown in Figs. 8 and 9.

The bolt 29 is formed with a hooked end 36 which provides a socket 37 for the reception of an extension 38 provided on the keeper 39. This keeper is pivotally mounted in a casing 40 and is provided with a downwardly extending arm 41 which is engaged by the hook 36 of the bolt 29 so as to rotate the keeper and cause the extension 25 38 to pass into the pocket 37. Bolt 30 is provided with a projecting lug 42 to lock the keeper from rotation and like the member 29 is provided with sweeps 34 and 35, at the terminal of the sweep 35 there being 30 however a nose 41', and it is also provided with recesses 31 and a slot 45 corresponding to those in member 29.

In operating the lock the bolt 30 is initially moved by the extension 9 coming in contact with the projection 41' and after such movement remains stationary until the sliding bolt 29 has been advanced by the extension 9 to a point where the openings 35 in the bolts 29 and 30 register. This is 40 accomplished by the extension 9 engaging the inner wall of the recess 35 of the bolt 29. From this point on the bolts move in unison until the hooked end of the bolt 29 engages the keeper 39 and causes the same 45 to assume the position shown in Fig. 10. Upon further movement of the extension 9 the bolt 30 will be advanced farther due to the fact that the extension 9 will still contact projection 41' on bolt 30. This latter movement causes the extension 42 of the bolt 30 to enter an opening 43 in the keeper which prevents the keeper from rotating

until the bolt 30 is again disengaged. The same movement and operation of the bolts can be accomplished by inserting the proper 55 key in the key hole 44 and causing the same to engage with the bolts by means of the aperture or recesses 34.

Slots 45 are provided in the bolts for the reception of a stop 46 which limits the 60 movement of the bolt so as to only rotate the keeper a part of a revolution to bring the aperture or opening 43 in the proper position for the reception of the extension 42 formed on the bolt 30.

For compactness of construction the bolt 29 is made of less thickness for a part of its length so as to accommodate or nest the body of the bolt 30, as shown in Figs. 10 and 11. Bolts 29 and 30 are arranged parallel to one another and are operated upon by the same operating device.

The foregoing description and the drawings have reference to what may be considered the preferred, or approved, form of 75 invention. It is to be understood that I may make such changes in construction and arrangement and combination of parts, materials, dimensions, etc., as may prove expedient and fall within the scope of the appended claim.

Having fully described my invention what I claim as new and desire to secure by Letters Patent is:

A lock comprising a keeper, a housing, a 85 latch pivotally mounted within the housing and adapted to engage the keeper, a sliding bar for operating the latch, a knob provided with a cam, means for advancing and retracting the bar upon the turning of the 90 knob and means for advancing and retracting the bar by a key, said means including a plurality of aligned sweeps on the bar, the cam coöperating with one sweep and the key with another, and a detent provided with a 95 pair of cam surfaces for coöperation respectively with the handle cam and the key.

In testimony whereof I affix my signature in presence of two witnesses.

MICHAEL MARINO.
